UNITED STATES PATENT OFFICE.

JOHN H. SKINNER AND DANIEL E. RILEY, OF ALLEGAN, MICHIGAN.

TRAIN-STOPPING APPARATUS.

1,158,734.

Specification of Letters Patent.

Patented Nov. 2, 1915.

Application filed July 28, 1914. Serial No. 853,669.

To all whom it may concern:

Be it known that we, JOHN H. SKINNER and DANIEL E. RILEY, citizens of the United States of America, residing at Allegan, in the county of Allegan and State of Michigan, have invented new and useful Improvements in Train-Stopping Apparatus, of which the following is a specification.

This invention relates to improvements in automatic train stopping apparatus and has particular application to electrically operated apparatus of this character.

In carrying out the present invention, it is our purpose to improve and simplify the general construction of automatic train stops and to provide train stopping apparatus whereby the propelling power of two trains approaching each other head on and entering the same block or track section will be automatically cut off and the brakes applied so as to bring such trains to a standstill and so avoid a collision. It is also our purpose to provide apparatus of the class described whereby a stationary train or car in a block or section of the track will be protected from the front and from the rear so that in the event of trains approaching the immovable train from the front and rear, such approaching trains will be automatically stopped.

A further object of our invention is to provide apparatus of the type set forth whereby trains will be protected at open switches and which will embrace the desired features of simplicity, efficiency and durability coupled with cheapness of cost in installation and maintenance.

With the above and other objects in view, the invention consists in the construction, combination and arrangement of parts hereinafter set forth in and falling within the scope of the claim.

In the accompanying drawings; Figure 1 is a diagrammatic plan view of automatic train stopping apparatus constructed in accordance with the present invention. Fig. 2 is a similar view of the car carried mechanism.

Referring now to the drawings in detail, 1, 1 designate parallel lines of rails forming the trackway, while 2, 3 indicate feeders arranged longitudinally of the trackway and

spaced apart. Extending longitudinally of the trackway and disposed at one side of the feeder 2 is a conductor 4 formed of sections 5 having the meeting ends thereof insulated one from another to divide the trackway into blocks *a*, *b*, *c*, etc. One end of each section 5 of the conductor overlaps the adjoining end of the adjacent conductor as at 6. Extending longitudinally of the trackway adjacent to the remaining feeder 3 and upon the outer side thereof is a second conductor 7 formed of a number of axially alining sections 8 placed end to end and having the meeting ends thereof insulated from one another as at 9, the section 8 of the conductor 7 corresponding with the sections 5 of the conductor 4 and coöperating therewith to divide the trackway into blocks. The end of each section 8 of the conductor 7 corresponding to the overlapped end of the companion section 5 of the conductor 4 is extended and overlaps the adjoining end of the adjacent section 8 as at 10. By means of the overlapping ends 6 and 10 of the sections 5 and 8 respectively of the conductors 4 and 7, the blocks of the trackway overlap one another so that trains will be protected at the meeting ends of the blocks as well as between the ends of the blocks.

Each car operating over the trackway is equipped with current collectors 11 and 12 adapted to ride upon the sections 5 of the conductor 4 and the overlapping ends of such sections respectively when the car is traveling in one direction upon the trackway, and upon the sections 8 of the conductor 7 and the overlapping ends 10 of such sections respectively when the direction of travel of the car is reversed; and with current collectors 13, 14 and 15 designed to ride upon the feeder 3, the sections 8 of the conductor 7 and the overlapping ends 10 of such sections respectively when the car is traveling in one direction, and upon the feeder 2, the sections 5 of the conductor 4 and the overlapping ends 6 of such sections respectively when the direction of movement of the car is reversed. The current collectors 11 and 12 are electrically connected to each other and to one side of a motor 16 by way of a wire 17, while the current collectors 13, 14 and 15 are electrically connected

to each other and to the remaining side of the motor 16 by way of a wire 18.

In the present instance, we have shown our invention installed on a steam railroad and in this connection we wish it to be understood that the invention, in its useful application, is not limited to use in conjunction with any particular type of railroad, as the same may be employed on electrically 10 propelled and other railways.

Mounted upon the shaft of the motor 16 is a drum and connected to the drum and wrapped thereabout is one end of a cable 26 or other flexible element, the remaining 15 end of the cable being passed through an opening in the handle of the throttle valve lever and secured to the finger piece of the latching rod of the throttle lever. The outer end of the shaft of the motor 16 is 20 equipped with a worm that meshes with a worm wheel and this worm wheel is provided with an outwardly extending crank pin connected through the medium of a link 32 with a lug 33 pivotally secured to the handle 34 of the engineer's brake valve 35. By means of this construction, it will be seen that when the motor is energized, the shaft thereof will be revolved to exert a pull 25 upon the rope 26 and so unlatch the throttle valve lever and swing the latter to closed position.

Simultaneously with the rotation of the drum, motion is imparted to the worm wheel 29 and the link 32 is reciprocated with 30 the effect to manipulate the engineer's brake valve to effect a gradual application of the brakes to the wheels, the motor shaft rotating independently of the drum 20 succeeding the movement of the throttle lever to 40 closed position, incident to the spring connection between the shaft and drum.

In Fig. 1 of the drawings, T and T' represent two trains approaching each other, train T being in block b and train T' in block c and entering block b. In this position of the trains, the motors 16 thereon are both energized, current flowing from the feeder 2 through the contact roller 13 to the contact roller 15 of train T', the overlapping end 6 and section 5 of the conductor 4, collector 11 on train T, wire 17, motor 16, wire 17, motor 16, wire 18 and collector 15 to collector 13 of train T and into the return feeder 3. Thus, the motor 50 16 of train T is energized. The current energizing the motor 16 on train T' flows from the feeder 2, through the current collector 13, the wire 17, motor 16 on train T', wire 18, current collector 11, particular section 55 8 of the conductor 7, the overlapping end 10 of such section, current collector 15 on train T, and back to the return feeder 3 by way of the current collector 13 on the last-mentioned train. Thus, the motors 16 60 on trains T and T' are connected in par-

allel with each other and in series with the feeders 2 and 3. Should train T' be immovable on the trackway, a train approaching the train T' head on will be brought to a standstill when within the danger zone as 70 just described and in order to protect the immovable train against a train approaching from the rear, as train T², a bridging piece 36 is employed and fastened to the rear end of train T' in engagement with 75 the return feeder 3 and the conductor 7 so as to electrically connect such feeder and conductor. Thus, when train T² enters the block occupied by train T', the motor 16 on train T² will be energized, current flowing 80 from the feeder 2, through the collector 13 on train T², wire 18, motor 16, wire 17, collector 11, particular section 8 of the conductor 7, and the bridging piece 36 to the return feeder 3. This bridging piece 36 is 85 employed only when the particular train is at a standstill on the trackway.

From the foregoing description taken in connection with the accompanying drawings, the construction and mode of operation of our improved train stopping apparatus will be readily apparent. It will be seen that we have provided an automatic train stop whereby two trains approaching each other head on are automatically 95 brought to a standstill when entering the danger zone; wherein a train approaching an immovable train from the front or rear will be automatically stopped before colliding with the stationary train and whereby 100 trains are protected at open switches.

We claim:

In train stopping apparatus, the combination with a trackway, of feeders arranged longitudinally of the trackway and spaced 105 apart, a conductor extending longitudinally of the trackway adjacent to one of said feeders and formed of sections insulated one from another to divide the trackway into blocks and each having one end 110 overlapping the adjoining end of the adjacent section, a second conductor extending longitudinally of the trackway adjacent to the remaining feeder and formed of sections corresponding to the sections of the 115 first feeder and having the confronting ends thereof insulated from one another and each having one end overlapping the adjoining end of the adjacent section corresponding to the overlapping end of the companion 120 section of the first-mentioned conductor; a set of car carried current collectors electrically connected and riding upon the sections of the first-mentioned conductor and the overlapping ends thereof respectively, 125 a second set of current collectors carried by the car and riding upon the sections of the remaining conductor, the adjacent feeder and the overlapping ends of said sections respectively and electrically connected to 130

one another, a motor connected in circuit with said sets of current collectors, means operable from said motor to bring the car to a standstill, and means on the rear end 5 of each car operable to bridge the last-mentioned conductor and the adjacent feeder to protect the car against rear end collisions.

In testimony whereof we affix our signatures in presence of two witnesses.

JOHN H. SKINNER.
